COMPARISON MICROSCOPE

Howard A. Maier, Williamsville, N.Y., assignor to
American Optical Corporation, Southbridge, Mass.

Filed Feb. 14, 1972, Ser. No. 226,367

Term of patent 14 years

Int. Cl. D16—06

U.S. Cl. D57—1 E

Fig. 1

Fig. 3

Fig. 4

FIG. 1 is a front elevation view of a comparison microscope according to my design;

FIG. 2 is a side elevation view of the same;

FIG. 3 is a perspective view from the front of a comparison microscope showing my new design; and

FIG. 4 is a perspective view from the rear of a comparison microscope.

The portions shown in broken lines do not form a part of the present design.

I claim:

The ornamental design for a comparison microscope, as shown.
